UNITED STATES PATENT OFFICE

JOHN GRIESINGER, OF LOS ANGELES, CALIFORNIA, ASSIGNOR TO THE NATIONAL MARKING MACHINE COMPANY, OF CINCINNATI, OHIO, A CORPORATION OF OHIO

LAUNDRY TAB AND METHOD OF AFFIXING IT TO LAUNDRY ARTICLES

Application filed April 25, 1932. Serial No. 607,357.

The object of my invention is to provide a laundry tab of simple, durable and inexpensive construction and of light weight designed to be quickly and easily affixed to laundry articles, and there held securely enough to withstand the usual laundry operations without becoming detached from the articles.

A further object is to provide an improved method of affixing my improved tabs to laundry articles in such a manner that the operations may be quickly and easily performed and tabs may be affixed to the laundry articles in such manner that they will not become detached during the ordinary laundry processes and at the same time may be readily and easily removed before delivery of the articles to the customers.

My invention consists in the construction, arrangement and combination of the various parts of the device, whereby the objects contemplated are attained, as hereinafter more fully set forth, pointed out in my claims, and illustrated in the accompanying drawing, in which:

Figure 1 shows a plan view of a tab in flat form.

Figure 2 shows an isometric view of same with the side margins folded up and a thread placed in position therein.

Figure 3 shows an isometric view of the complete tab in folded position with attaching thread in place; and

Figures 4, 5 and 6 show my improved tabs applied to laundry articles, each having the same identification mark on the tab, but each being distinguished from the other because of the color of the thread used in affixing it to the garment, and the color of the tab body.

At one end of the tab are two thread receiving openings 11 widely spaced from each other. At each side of the body is a marginal edge portion 12 and at the end of the body opposite from the openings 11 is the end margin 13.

The method of applying the tab to a laundry article is to first take a short section of thread and extend both end portions at the same time through the laundry article 14 and through the openings 11. The end portions of the thread are then laid longi-

tudinally across the entire body of the tab to points extended beyond the end of the tab opposite from the openings, as shown in Figure 2.

Then while these thread ends are held in this position, the side margins 12 are bent over the thread portions and over the body, as shown in Figure 3, and finally the end portion 13, together with the ends of the thread, is bent over the body portion and over the threads and over the previously folded side margins.

By this method a very firm grip is obtained upon the threads and the central portion of the thread is extended straight across one face of the tab between the openings 11, where it may be readily and easily seen by any one inspecting the tab.

Before attaching the tabs to the articles, the tabs are provided with an identification mark, preferably by embossing it in the body of the tab by a suitable die, and a number of lots of tabs having bodies of different colors are provided. These tabs are fixed to the laundry articles by thread, and I also provide a number of lots of threads of different colors. In Figure 4 the tab is shown to be of blue color and the thread 15 of red color. In Figure 5 the tab is white and the thread 16 is blue. In Figure 6 the tab body is red and the thread white.

In the specification I have referred to the tab as a laundry tab, and while it is especially designed for use in laundries, I wish to be understood as not limiting my claims to the use of this tab for laundry purposes only.

I claim as my invention:

1. A laundry tab comprising a body portion of bendable material having two openings near one end, a thread extended through said openings and transversely across one side of the tab and also longitudinally along both edge portions of the opposite side of the tab, the side marginal portions of the tab being folded over said longitudinally extended portions of the thread and an end marginal portion of the tab being folded over the folded side marginal portions and over the thread end portions.

2. The method of attaching tabs to laundry articles.

dry articles which consists in first providing a tab body of bendable material, then extending a thread through one end of the tab and through a laundry article with the central portion of the thread extended across one side of the tab, then extending the thread longitudinally along the opposite side of the tab near both side edges, then folding the side marginal portions of the tab over the longitudinally extended thread portion, and finally folding an end of the tab over the said folded side marginal portions and over the end portions of the thread.

15 JOHN GRIESINGER.
